Eli E. Hendrick, INVENTOR

BY
H. Graham
ATTORNEY

UNITED STATES PATENT OFFICE.

ELI E. HENDRICK, OF CARBONDALE, PENNSYLVANIA.

DESIGN FOR FILTER-PRESS RING.

SPECIFICATION forming part of Design No. 22,918, dated November 28, 1893.

Application filed October 19, 1893. Serial No. 488,650. Term of patent 14 years.

To all whom it may concern:

Be it known that I, ELI E. HENDRICK, a citizen of the United States, residing at Carbondale, Lackawanna county, and State of Pennsylvania, have invented and produced a new and original Design for Filter-Press Rings or Plates, of which the following is a specification.

Referring to the accompanying drawings forming a part hereof:—Figure 1 is a face view of a filter press ring or plate showing my design; and Fig. 2 is an edge view of the same.

The leading feature of the design for a filter-press ring or plate consists in the projecting upper ear *a* extending outwardly from the filter press ring or plate *b* and a projecting lower ear *c* also extending outwardly from said ring or plate *b*, and separated a short distance from the ear *a*. The upper ear *a* is a comparatively long one, having a straight under surface merging by a concave curve into the lower ear *c* which is a comparatively

short one, that is to say much shorter than the upper ear *a*. The top surface of the upper ear *a* merges by a curve into the circumference of the ring or plate *b* and the under surface of the lower ear *c* likewise merges into the circumference of the ring or plate; the two ears and the ring or plate being formed integral. The filter-press ring or plate is formed as shown upon diametrical opposite sides of its circumference with a long and short ear, the ears on one side being a complement of those on the opposite side, a short distance or space being left between the upper and lower ears.

What I claim is—

The design for a filter-press ring or plate, substantially as shown and described. 40

In witness whereof I have hereunto signed my name in the presence of two witnesses.

ELI E. HENDRICK.
